United States Patent Office.

HIRAM W. RANSOM, OF LAWRENCEBURG, INDIANA.

Letters Patent No. 74,422, dated February 11, 1868.

IMPROVEMENT IN FIFTH-WHEELS FOR CARRIAGES.

The Schedule referred to in these Letters Patent and making part of the same.

TO ALL WHOM IT MAY CONCERN:

Be it known that I, HIRAM W. RANSOM, of Lawrenceburg, in the county of Dearborn, and State of Indiana, have invented a new and improved Non-Rattling Fifth-Wheel for Carriages, of which the following is a full and clear description, reference being had to the accompanying drawings, and to letters of reference marked thereon.

The nature of my improvement consists in the construction of an adjustable metallic slide, placed in the safety-guide in a manner to apply a block of India rubber to prevent the fifth-wheel from rattling.

Figure 1 represents a perspective view of my improved fifth-wheel.

Figure 2 is a transverse section of the same.

A is the head-block, to which are attached, in the usual manner, the spring B, reach C, and half-circle D. E is the forward axle, with the fifth-wheel F fastened to it. The rear part of the fifth-wheel is held in a horizontal position with the reach by means of the safety-guard G. The safety-guard is constructed in a manner to receive a metallic slide-block, H, which is fitted into safety-guard G, with projections at the corners to keep it in place, and is adjustable up and down by means of the India-rubber block I, that is held in a chamber in the lower part of the slide-block H, resting above the bottom of safety-guard G.

The advantage of the application of India rubber in connection with the fifth-wheel is that the vehicle is allowed to vibrate freely back and forth in turning around, and, as the surfaces of the fifth-wheel become worn by use, they are kept from rattling by the constant and uniform pressure of the elastic block of India rubber; consequently become more durable.

I do not wish to confine myself to the use of India rubber, as metallic springs would be equivalent. The slide-block H would be made of brass, in order to secure durability in connection with the iron fifth-wheel.

Having described my improved fifth-wheel, I make the following claim, which I desire to secure by Letters Patent:

The block H, which forms a bearing for the fifth-wheel F, and which is provided with a wing on each side, whereby the rubber D is held in the safety-guard G, as and for the purposes set forth.

HIRAM W. RANSOM.
